Patented Apr. 19, 1966

204,452

MULTIPLE SEATING UNIT

Thomas G. Walkinshaw, Mission, Kans., assignor to
Cramer Industries, Inc., Kansas City, Kans., a corpora-
tion of Missouri

Filed May 10, 1965, Ser. No. 85,192

Term of patent 14 years

(Cl. D15—8)

Des. 204,452

PAGE 2

FIG. 1 is a front perspective view of a Multiple Seating Unit; and

FIG. 2 is a rear perspective view thereof.

FIG. 3 is a fragmentary front elevational view of the unit showing one of the seat members on an enlarged scale; and

FIG. 4 is a top plan view thereof.

The dotted line showing of a base support in FIGURE 1 is for illustrative purposes only.

I claim:

The ornamental design for a multiple seating unit, as shown and described.
